UNITED STATES PATENT OFFICE.

CARLOS L. YOUNG, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

MEANS AND METHOD OF WINDING LOOM BOBBINS.

Application filed March 21, 1928. Serial No. 263,470.

This invention relates to bobbins used in automatic weft replenishing looms. In such looms it is customary to wind a preliminary bunch of weft or filling on the butt of the 5 bobbin, to furnish a reserve supply of weft for use between the indication of substantial weft exhaustion and the transfer of the exhausted weft carrier.

When weaving silk or rayon, it has been 10 found that the weft end leading to this preliminary bunch was frequently pulled out in handling and that the bunch was then often entirely unwound from the butt of the bobbin, in which case the bobbin would run out 15 immediately after indication and before transfer could take place.

It is the general object of my invention to 20 provide a bobbin in which the weft end may be so disposed that it will not become loosened or displaced in handling. A further object is to provide a special device by which the weft end may be threaded into the bobbin in such a way as to be securely retained 25 therein, and I have also provided a simple and convenient threading mechanism for use in conjunction with my improved bobbin.

My invention further relates to arrangements and combinations of parts which will be hereinafter described and more particularly pointed out in the appended claims.

A preferred form of the invention is shown 30 in the drawings in which

Fig. 1 is a plan view of portions of a winding machine embodying my improvements;

Fig. 2 is a side elevation, looking in the direction of the arrow 2 in Fig. 1;

Figs. 3 and 4 are partial plan views showing the successive steps in the threading operations; and

Fig. 5 is a sectional side elevation, taken 40 along the line 5—5 in Fig. 3.

Referring to the drawings, I have shown parts of a winding machine of a usual commercial construction and including a spindle 10 mounted to rotate at high speed in suitable bearings in a frame 11. The bobbin B is held by friction on the spindle 10 and the butt of the bobbin preferably engages a washer 12 of rubber or leather, or other suitable material for a purpose to be described. A reciprocating builder rod 14 is mounted 45 parallel to the spindle 12 and supports a

winding head 15 by which the yarn is led to the bobbin for the usual traverse and winding operation.

A rod 20 is mounted in the frame 11 and may also be supported by a bearing projection 22. At its outer end, the rod 20 takes the form of a fixed spindle 24 adapted to receive the bobbin B.

The bobbin B is of the usual construction, but is provided with one or more openings 25 (Fig. 5) extending axially through the butt of the bobbin near the periphery thereof and just inside of the bobbin rings 26.

The rod 20 has a disc or washer 28 secured thereto from which a hook needle 30 projects axially outward. When the bobbin B is placed on the spindle 24, it is turned until the hook 30 is aligned with one of the openings 25, and the bobbin is then pushed further along the spindle until it engages the plate or washer 28. When in this position, the hook 30 extends through and beyond one of the openings 25 as indicated in Fig. 3.

The weft end W to be wound on the bobbin is then inserted in the hook of the needle 30 and the bobbin is withdrawn from the spindle 24, as indicated in Fig. 4, thus threading the weft W through the opening 25. The bobbin is then mounted on the regular winding spindle 10 and the end of the weft W is held between the butt of the bobbin and the friction washer 12.

The weft may then be guided by a bunch building fork 32, while a sufficient amount of weft is wound on the bobbin to provide the desired weft reserve. It is not entirely necessary to use the bunch building fork 32, as the weft may be and often is, held in the hand of the operator. After the bunch is wound, the winding head 15 is threaded up and the winding of the bobbin is completed in the usual manner.

After the bobbin is wound and removed, the initial end of the weft W still extends through the opening 25 and is thus not liable to be caught or unwound during the handling of the bobbin. Consequently the full amount of reserve weft is available after indication 95 of weft exhaustion.

Having thus described my invention and the advantages thereof, I do not wish to be limited to the details herein disclosed, other-

wise than as set forth in the claims, but what I claim is:—

1. A weft bobbin having a weft receiving opening extending through the butt of said bobbin and parallel to the axis thereof but offset laterally therefrom.

2. A weft bobbin having a weft receiving opening extending through the butt of said bobbin parallel to the axis thereof and adjacent the periphery of said butt.

3. A device for threading weft in a bobbin having an offset axially extended opening in the butt thereof, comprising a fixed spindle to receive the bobbin, and a hook needle mounted in fixed position parallel to said

spindle and positioned to extend through said opening in the butt of the bobbin when the bobbin is mounted on said spindle.

4. The method of winding a bobbin which consists in threading the initial weft end through an offset, axially extended hole in the butt of the bobbin, confining the weft end to prevent withdrawal therefrom, winding a bunch on said bobbin while the weft end is thus confined, and thereafter completing the regular winding of the bobbin.

In testimony whereof I have hereunto affixed my signature.

CARLOS L. YOUNG.
